UNITED STATES PATENT OFFICE.

GEORGE C. SHERMAN, OF WAUKEGAN, ILLINOIS.

TOE-WEIGHT.

SPECIFICATION forming part of Letters Patent No. 241,735, dated May 17, 1881.

Application filed March 29, 1881. (No model.)

To all whom it may concern:

Be it known that I, GEORGE C. SHERMAN, a citizen of the United States, resident at Waukegan, in the county of Lake and State of Illinois, have invented certain new and useful Improvements in Toe-Weight Attachments for Horseshoes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a top view, showing the attachment applied. Fig. 2 is a sectional view.

This invention relates to improvements in attachments for horseshoes for securing toe-weights thereto.

The invention consists in the construction hereinafter set forth and claimed.

In the annexed drawings, the letter A represents an ordinary horseshoe provided with the upturned toe-clip a, through which is made a hole, a', on a line with the top of the shoe. In the front of the shoe, below hole a', is formed a recess, a².

The letter B represents a bolt having the end hook, b, adapted to catch on the inner surface of the shoe, and provided with a threaded shank, b', adapted to receive a nut, C.

The letter D represents a spur having its shank d dovetailed in cross-section, the broader part above, and provided with an enlarged head, d', fitted on the under side to the clip a, 35 and having the hole d², and below it the projection d³, the former registering with hole a', the latter fitted to recess a². The bolt B is slipped through hole a' from the rear, and its hook b caught against the inner surface of the 40 shoe. The spur D is put in place, the protruding end of shank b' entering the hole d² and extending beyond. The projection d³ is placed into recess a², the enlarged head d' of the spur resting on the clip, and all held by nut C. 45

Weights of any desired size, having grooves to fit the spur d, can be slipped upon the latter.

I claim—

In a toe-weight, the combination of the shoe A, having recess a² and clip a, provided with 50 hole a', bolt B, nut C, and spur D, having projection d³ and hole d², substantially as and for the purposes set forth.

In testimony whereof I affix my signature in presence of two witnesses.

GEORGE C. SHERMAN.
